(57) **CLAIM**

The ornamental design for a hand-held navigational device, as shown and described.

DESCRIPTION

FIG. 1 is a perspective view of a hand-held navigational device according to the present invention;

FIG. 2 is a front elevation view thereof;

FIG. 3 is a left side elevation view thereof;

FIG. 4 is a right side elevation view thereof;

FIG. 5 is a rear elevation view thereof;

FIG. 6 is a top plan view thereof; [and]

FIG. 7 is a bottom plan view thereof;

FIG. 8 is a perspective view of a hand-held navigational device according to the present invention;

FIG. 9 is a front elevational view thereof;

FIG. 10 is a left side elevational view thereof, with the right side being a mere image of the left side;

FIG. 11 is a top plan view thereof; and,

FIG. 12 is a bottom plan view thereof.
